UNITED STATES PATENT OFFICE.

AUGUSTUS N. BUCKNER, OF BIRMINGHAM, ALABAMA.

TRANSIT.

971,523.

Specification of Letters Patent.

Patented Oct. 4, 1910.

Application filed June 2, 1909. Serial No. 499,658.

To all whom it may concern:

Be it known that I, AUGUSTUS N. BUCKNER, citizen of the United States, residing at Birmingham, in the county of Jefferson and

5 State of Alabama, have invented certain new and useful Improvements in Transits, of which the following is a specification.

This invention comprehends certain new and useful improvements in transits, and 10 the invention has for its object an improved device of this character which is simpler and less expensive than the transits in customary use, and which is designed particularly for mechanics' use and for other purposes where absolute accuracy is not required, the device being provided with a 15 novel scale which indicates for different vertical angles the rise or depression for a certain distance running.

20 A further object of the invention is an improved leveling device that admits of the instrument being quickly and accurately leveled with respect to the stand to compensate for unevenness of the supporting surface.

25 With these and other objects in view that will more fully appear as the description proceeds, the invention consists in certain constructions and arrangements of the parts 30 that I shall hereinafter fully describe and then point out the novel features of in the appended claims.

35 For a full understanding of the invention and the merits thereof and also to acquire a knowledge of the details of construction, reference is to be had to the following description and accompanying drawings, in which:

40 Figure 1 is a side elevation of my improved transit; Fig. 2 is a horizontal section on the line *a—a* of Fig. 1; Fig. 3 is a similar view, the section being taken on the line *b—b* of Fig. 1; Fig. 4 is a transverse vertical section; Fig. 5 is a fragmentary section showing the clamp in operative position; and, 45 Fig. 6 is a detail perspective view of the links detached.

50 Corresponding and like parts are referred to in the following description and indicated in all the views of the drawings by the same reference characters.

55 My improved instrument embodies superposed circular plates or platforms 1 and 2 that are arranged concentrically, the upper plate 2 being relatively smaller than the lower or main plate 1 and being designed for

rotation relative thereto. In the present instance the plate 2 is rotatably mounted on a vertical spindle 3 that upstands from the main plate 1 and is seated in a central opening 4 in the latter, the opening preferably extending entirely through the main plate and the spindle being rigid with a bottom plate 5 secured beneath the plate 1 for this purpose. The upper plate 2 is supported 60 upon and movable over blocks 6 provided on the upper face of the main plate to maintain the two plates in the desired spaced relation.

The sighting apparatus is carried by the 70 upper plate 2 and in the present instance consists essentially of a beam 7 that is fulcrumed at an intermediate point on a bolt 8 in order to turn freely about a horizontal transverse axis. The bolt extends between 75 spaced standards 9 which are attached to the upper face of the plate 2 and which are provided at suitably elevated points with registering openings through which the bolt is passed, one of the openings being threaded 80 for engagement with the extremity of the bolt in order to hold the same against accidental displacement. The head of the bolt is preferably winged whereby to admit of its ready manipulation. Stanley sights 10 85 are secured at the opposite ends of the beam 7, so that the same may be employed in lieu of a telescope.

The vertical position of the beam is read 90 on a protractor scale 11 provided at one face 90 of a vertical plate 12 which is carried by one of the standards 9. The zero or base line of this scale extends horizontally and is arranged to correspond with the upper edge 95 of the beam in the horizontal position of the same. Series of oblique lines are arranged above and below the horizontal line and intersect the same to lay off vertical angles of different sizes, the oblique lines being all disposed tangentially with respect to an imaginary circle described about the fulcrum point of the beam and having a radius equal 100 to the perpendicular distance between the fulcrum point and the base line of the scale.

105 When the beam is swung upwardly or downwardly about its axis its upper edge is arranged to be brought successively into correspondence with the respective oblique lines, the angles between the said oblique line and the base line being thus equal to 110 the vertical angle at which the beam is elevated or depressed. The oblique lines are

preferably designated by series of numerals which indicate the number of inches rise or depression to one foot running, for the respective angles.

5 The beam 7 is held in different vertically adjusted positions by means of a clamp disposed on the upper portion of the plate 12. This clamp comprises a vertically movable slide 13 which is mounted in a bearing strap 14 and is further guided by headed studs 15 projecting from the plate 12 in proximity to its opposite side edges. A threaded post 16 outstands from the lower end of the slide and has mounted thereon, an attaching ear 17 upstanding from the middle point of an arch-shaped clamping spring 18. The extremities of the spring 18 are turned to constitute feet 19 which bear against the upper edge of the beam 7 at longitudinally spaced 20 points on opposite sides of the fulcrum bolt 8. The attaching ear 17 is adapted to turn on the post 16 and is retained on the latter by a winged nut 20, the nut being designed to be tightened in order to hold the arch-shaped clamping spring 18 in different positions relative to the slide to conform to the vertical position of the beam. The slide 13 is prevented from moving vertically after the parts of the clamp have been adjusted, 25 by means of a set screw 21 working in the bearing strap 14.

The periphery of the disk 2 is graduated in degrees, as indicated at 22, for the purpose of measuring horizontal angles, the 30 measurements being indicated by a pointer 23 which is carried by a clip 24 embracing the edge of the main plate 1. Vertical and horizontal set screws 25 are mounted in the clip to admit of the adjustment of the same 35 with respect to the main plate. One or more guides 26 extend upwardly from the portion of the main plate that projects beyond the upper plate 2, and have their upper ends turned inwardly over the latter 40 to insure against the upward displacement of the same. Screws 27 are mounted in each of the guides and are adapted to impinge against the upper plate to clamp the same in 45 position.

50 The instrument is mounted on a stand or base 28 that, in the present instance, is in the form of a box-like casing having an open lower end and preferably supported on tripod legs 29, the latter being pivoted between pairs of ears 30 outstanding from the casing. As best seen in Fig. 4, the main plate and stand are connected by a ball and socket joint, the ball 31 being rigidly secured to the bottom plate 5 and being seated 55 in a socket member 32 fitted in the upper end of the casing. A stem 33 is rigid with the ball 31 and depends therefrom and projects through and has play in an opening 34 formed in the bottom of the socket member 32. Leading upwardly from the lower

end of the stem are two diametrical slots 35 which intersect substantially at right angles and are provided for the accommodation of crossed links 36. The links are in the form of rectangular plates and are oppositely and vertically slotted as indicated at 37, whereby to interlock and bring their upper and lower edges flush with each other. The ends of the links project outwardly beyond the periphery of the stem 75 and have pairs of adjusting rods 38 and 39 pivoted thereto at their inner ends to turn about transverse horizontal axes.

It is to be particularly observed that the adjusting rods of each pair are disposed in 80 alinement and are arranged at right angles to the line of the rods of the other pair. The rods all lie in the same horizontal plane and project outwardly through horizontal slots 40 in the adjacent sides of the casing and 85 also through slotted plates 41 secured on the exterior of the casing in registry with the said slots. Winged nuts 42 are threaded on the projecting extremities of the rods and are designed to be tightened against the 90 plates 41 to hold the stem against any lateral movement and thereby lock the ball 31 against movement in the socket member 32. By backing off the nut on one of the adjusting rods of one of the pairs, say the pair 95 designated 38, and advancing the nut on the other rod 38, the stem 33 may be swung laterally in one direction to move the ball in the socket member and effect the adjustment of the plates 1 and 2 with respect to 100 the stand, as it may be necessary to level the plates in case the tripod is placed on uneven ground. Upon the said lateral movement of the stem, the adjusting rods 39 slide in the corresponding slots 40 and plates 41, 105 so as not to interfere with the necessary adjustment. However, should it become necessary to adjust the plates 1 and 2 at right angles to the aforesaid adjustment, this may be conveniently accomplished by operating 110 the nuts on the adjusting rods 39. The slots 40 are preferably flared inwardly, as shown in Fig. 4, to admit of the adjusting rods having a limited turning movement about their pivots during swinging movement of 115 the stem.

The links 36 are detachably held in place by a sleeve 43 which is threaded on the lower extremity of the stem below the links and serves to force the latter upwardly against the upper end walls of the slots 35. A cap 44 screws on the sleeve. This cap is formed with central and side guide openings 45 through which is threaded a line 46 having a plumb-bob 47 attached to the lower end 120 thereof. The upper end of the line passes through the open lower end of the casing and is wrapped about a button or projection 48 provided on the exterior thereof. By virtue of this arrangement, the line 46 may 125

be conveniently wound and unwound from the button to effect necessary vertical adjustment of the plumb-bob.

In the practical use of an instrument constructed in accordance with my invention, suppose for instance, it is desired to ascertain the height of a flag pole or some similar object, the device is set up at some distance from the pole and the beam 7 is placed in a horizontal position and sighted at the pole, the level being suitably marked on the latter. The beam is then swung upwardly and sighted at the top of the pole and the angle of elevation read on the protractor scale 11. 10 Inasmuch as the scale is marked to indicate for the different vertical angles the number of inches rise or fall to one foot running, the height of the pole from the level mark to the top may be readily calculated in 15 inches by multiplying the number of inches rise for the vertical angle by the number of feet in the distance of the instrument from the pole. The total height of the pole is found by measuring the distance of the level 20 mark on the pole above the ground and adding this to the height previously calculated. The manner of using the instrument in measuring horizontal angles will be 25 obvious.

30 From the foregoing description in connection with the accompanying drawings, it will be apparent that I have provided an improved transit which is susceptible of various uses and may be advantageously employed in laying out gardens and the like; which is simple and durable in structure and quite accurate; and which is composed of comparatively few parts that may be easily and cheaply manufactured and readily assembled.

Having thus described the invention what is claimed as new is:

1. A leveling device including a stand, a member adapted to carry an instrument and having a universal joint connection with the stand, the stand being formed with a plurality of openings, a plurality of rods positively connected at one end to the member and radiating therefrom and passing freely 45 through the said openings, and nuts threaded on the free ends of the rods to hold the member in adjusted relation to the stand.

2. A leveling device including a stand, a stem adapted to carry an instrument and having a universal joint connection with the stand, a plurality of rods positively connected at one end to the stem radiating therefrom and arranged in pairs, the rods of each pair being disposed in diametrical 55 alignment and being positioned at right angles to the rods of the other pair, the stand being formed with openings through which the free ends of the rods pass freely, and nuts working on the free ends of the 60 rods to hold the stem in adjusted relation to

the stand, the openings being elongated to afford the rods sliding movement therein by and upon the adjustment of the stem.

3. A leveling device including a stand, a stem adapted to carry an instrument and having a universal joint connection with the stand, the stand being formed with a plurality of openings extending therethrough, a plurality of rods pivotally connected at one end to the stem and radiating therefrom and passing freely through the openings, and nuts working on the free ends of the rods, the said openings being flared to permit the limited turning movement of the rods about their pivots by and upon the 75 adjustment of the stem.

4. A leveling device including a stand, a stem adapted to carry an instrument and having a universal joint connection with the stand, links passed transversely through the 80 stem with their ends projecting therebeyond, and rods positively connected at one end to the projecting ends of the links and having adjustable connection at their other 85 ends with the stand.

5. A leveling device including a stand, a stem adapted to carry an instrument and having a universal joint connection with the stand, members rigid with the stem and projecting radially outwardly therefrom at 90 right angles to each other, rods pivotally connected at one end to said members and having adjustable connections at their other ends with the stand.

6. A leveling device including a stand, a stem adapted to carry an instrument and having a universal joint connection with the stand, the stem being formed with intersecting slots passing transversely therethrough at right angles to each other, and 100 crossed links fitted in the respective slots with their end portions projecting outwardly from the stem, the links being interlocked to be held against withdrawal from the slots, and means connected to the projecting ends of the links for holding the 105 stem in adjusted relation to the stand.

7. A leveling device including a stand, a stem adapted to carry an instrument and having a universal joint connection with the 110 stand, the stem being formed with intersecting slots extending transversely therethrough at right angles to each other and leading from one end of the stem, crossed links inserted longitudinally in the respective slots with their ends projecting beyond the stem, the links being interlocked to be held against lateral displacement from the slots, removable means for holding the links against longitudinal displacement from the 115 slots, and means connected to the projecting ends of the links for holding the stem in 120 adjusted relation to the stand.

8. A leveling device including a stand, a stem adapted to support an instrument and 125

having a universal joint connection with the stand, the stem being formed with intersecting slots passing transversely therethrough and leading from one end thereof and disposed at right angles to each other, crossed links adapted to be inserted longitudinally into the respective slots with their end portions projecting outwardly beyond the stem, the links being interlocked to be held against lateral displacement from the slots, a member threaded on the stem for holding the links against longitudinal displacement from the slots, and means connected to the projecting ends of the links for holding the stem in adjusted relation to the stem.

9. A leveling device including a stand, a stem adapted to support an instrument and having a universal joint connection with the stand, a plurality of rods radiating from the stem and pivotally connected at one end thereto to turn about axes which are perpendicular to the length of the stem, the other ends of the rods being adjustably con-

nected to the stand to hold the stem in adjusted relation thereto.

10. A leveling device including a substantially vertically disposed hollow stand, a stem adapted to support an instrument and mounted within the stand and having a universal joint connection therewith, a plurality of rods positively connected at one end to the stem and radiating therefrom, the stand being formed in its sides with openings through which the ends of the rods pass freely, and nuts working on the free ends of the rods and bearing against the sides of the stand, the said openings being substantially horizontally elongated to afford the rods lateral sliding movement therein by and upon the adjustment of the stem.

In testimony whereof I affix my signature in presence of two witnesses.

AUGUSTUS N. BUCKNER.
